United States Patent Office.

WILLIAM MOORE, OF KOKOMO, INDIANA.

Letters Patent No. 78,885, dated June 16, 1868.

IMPROVEMENT IN WATER-INDICATORS FOR STEAM-GENERATORS.

The Schedule referred to in these Letters Patent and making part of the same.

TO ALL WHOM IT MAY CONCERN:

Be it known that I, WILLIAM MOORE, of Kokomo, in the county of Howard, and State of Indiana, have invented a new and useful Water-Governor for Steam-Boilers; and I do hereby declare that the following is a full, clear, and exact description thereof, reference being had to the accompanying drawings, and letters of reference marked thereon, which will enable others skilled in the art to make and use the same.

Figure 1 is a side elevation,

Figure 2 a longitudinal section,

Figure 3 a section of valve, and

Figure 4 a transverse section.

Like figures denote the same parts.

The object of this invention is to so regulate the amount of steam admitted to the pistons of the steam-pumps, as to make them self-regulating, that is, to cause the pumps to supply more water when more water is needed, and less when less is needed. This I do by connecting rods or levers to a float in a peculiar manner. This is an appendage to my improvements in automatic steam-boiler feeders, and are auxiliaries of each other.

Fig. 1 shows the general shape of my apparatus. E is an index-hand or lever, balanced by a weight, and indicating by a dial the amount of water in the boiler.

Fig. 2 shows the manner of connecting the different rods or levers to the float in the boiler with the hollow valve Y, which works up and down in the sleeve o o o o. E' is the pipe conveying steam to the pumps. The valve has side apertures or slots S, and as the water rises in the boiler, there is less of the aperture opposite to the receiving-pipe E', and consequently less steam will be admitted to the pumps, and they in consequence will supply less water, and as the water gets lower in the boiler, the reverse of this is true.

Fig. 4 shows the manner of attaching the apparatus to a steam-boiler, and also the alarm-arrangement, which is the same as that described in the application for my automatic boiler-feeder.

Having thus fully described the nature of my said invention, what I desire to secure by Letters Patent, is—

The arrangement of the hollow valve Y, with its side apertures S, the sleeve o o, connecting-rod R, lever D, and the float and its rod B, all constructed, arranged, and operating substantially in the manner herein specified.
